DESIGN FOR A HANDBAG

Irving Kaplan, Bronx, N. Y.

Application January 27, 1941, Serial No. 98,390

Term of patent 7 years

To all whom it may concern:

Be it known that I, Irving Kaplan, a citizen of the United States and resident of the Bronx, New York, in the county of Bronx and State of New York, have invented a new, original, and ornamental Design for a Handbag, of which the following is a specification, reference being had to the accompanying drawing, forming a part thereof, and of which Figure 1 is a view in front elevation of a handbag showing my new design; Fig. 2 is a view thereof in end elevation; and Fig. 3 is a fragmentary sectional view of the hand-

bag fabric showing the ribs as they appear wherever shown.

The rear of the handbag is the same as the front view thereof.

The characteristic features of the design reside in the raised ornamentation on the sides of the bag having the specific configuration and arrangement shown.

I claim:

The ornamental design for a handbag, substantially as shown and described.

IRVING KAPLAN.
